BABY BONNET

Adam T. Pagliaro, Conshohocken, Pa.

Application August 17, 1954, Serial No. 31,901

Term of patent 3½ years

(Cl. D3—13)

FIG. 1

FIG. 2.

FIG. 3.

Figure 2 is a perspective view looking to the front and at one side of the bonnet; and

Figure 3 is a perspective view looking to the rear and at the other side of the bonnet.

I claim:

The ornamental design for a baby bonnet, as shown.
